UNITED STATES PATENT OFFICE.

JOHN W. KEOGH, OF PHILADELPHIA, PENNSYLVANIA, ASSIGNOR TO FEDERATION OF COLLEGE CATHOLIC CLUBS, OF PHILADELPHIA, PENNSYLVANIA, A FRATERNITY.

DESIGN FOR A BADGE.

Application filed July 24, 1925. Serial No. 14,199. Term of patent 14 years.

To all whom it may concern:

Be it known that I, JOHN W. KEOGH, a citizen of the United States of America, residing at Philadelphia, in the county of Philadelphia and State of Pennsylvania, have invented a new, original, and ornamental Design for a Badge, of which the following is a specification, reference being had to the accompanying drawing, forming a part hereof.

In the drawing:

Fig. 2 is an edge view of the same.

I claim:

The ornamental design for a badge, as shown.

JOHN W. KEOGH.
